UNITED STATES PATENT OFFICE.

GEORGE PAGE, OF KEENE, NEW HAMPSHIRE.

MACHINE FOR EXCAVATING AND EMBANKING DITCHES.

Specification of Letters Patent No. 993, dated October 26, 1838.

To all whom it may concern:

Be it known that I, GEORGE PAGE, of Keene, in the county of Cheshire and State of New Hampshire, have invented a new and Improved machine for the Purpose of Ditching and Embanking; and I do hereby declare that the following is a full and exact description thereof.

This machine is to be operated upon by the power of horses, or other animals, walking in a circle, and drawing a lever, or sweep. This sweep is attached to a vertical shaft, carrying a drum, around which, a chain, or rope, is wound, by the revolution of the shaft; the other end of said rope, or chain being attached to any fixed object in advance of the machine; which is, consequently, moved forward with a velocity proportioned to the size of the drum. In the rear of the carriage which supports the machinery, I place my excavating wheel, or excavator, by means of which the bottom and sides of the ditch are to be cut, the earth elevated, and thrown upon an inclined plane, by which it is deposited on the side of the ditch to form an embankment. To this excavating wheel the requisite motion is communicated by gearing from the vertical shaft which is turned by the horse. In the accompanying drawings, Figure 1, represents a top view of the machine; Fig. 2, a side view of the excavating wheel, the inclined plane, and a part of the carriage; Fig. 3, represents the inclined rims of the excavating wheel, with their cutting edges, and the vibrating receivers for containing, elevating, and discharging the soil; the serrated ring I, I, which forms one face of the wheel as seen in Fig. 2, being removed to show them distinctly. It is intended sometimes to omit the serrated rims which constitute the circumference of the wheel, and to use two, or any other convenient number of arms, which are to carry the cutting edges of the excavation, and the vibrating receivers for the soil; a side view of this modification of the apparatus is shown at Fig. 4, together with the manner of gearing to convey motion from the vertical shaft to the excavator. Fig. 9, represents an end view of the machine, with the wheels attached to the slides for adjusting the depth of the excavating wheel, like parts in this figure being designated by the same letters of reference as in other figures. Fig. 5, is

an edge view of the excavator, sustained upon arms.

In Fig. 1, A, A, is the frame work of the machine, having in its rear the excavating wheel B, B, revolving with the main axis C, C, which runs in boxes in the vertical timbers of the frame A', Fig. 2. The wheels may be placed upon axles x, x, attached to slides r, r, Figs. 2, 7, and 9. q represents a screw passing through a projection from the frame, and pressing upon a projection from the slide r, by raising or lowering the screw the slide is to be adjusted. A projection t, represented by dotted lines in Figs. 7, and 8, moves in the slot u, and keeps the upper part of the slide in its place, while the lower part passes behind the bar v and between the bolts w, w, which attaches the bar to the frame. The side piece A, A of the frame, when the machine is in use in soft soil, rest upon ways consisting of planks placed upon the ground; these ways are to be removed and carried forward, as the machine advances. E, is the lever, or sweep, to which the horse is attached, and which carries the drum, F, Fig. 4, around which the rope G, is to be wound. The shaft H, is driven by the bevel gear a, a', on its end, and on the axis of F, and by a similar gearing b, b', at its opposite end, a revolving motion is given to the excavating wheel as shown clearly in Fig. 4, the pinion c, in that figure, being on the same shaft with b', and gearing into the wheel c', which wheel is attached to the shaft and arms of the excavator, or to the side of the excavating wheel. To guide the machine I use two wheels d, d, made thin so as to cup into the ground, their axle turning upon a center pin, so that its direction may be changed by moving the lever d' in the manner indicated in the drawing; when it is desired to advance more slowly than usual, this may be effected by the slackening of the rope on the drum F. The edges e, e, of the excavating wheel B, B, are serrated, and at such distance apart as is equal to the width of the ditch to be made. These serrated edges are shown in the side view Figs. 2, and 3. The side of the wheel on which the gearing is placed, is one continuous sheet of metal, but the opposite side shown in Fig. 2, has a face rim I, I, extending inward from the serrated edge to such distance only as is necessary to embrace the receivers for containing the excavated earth. 100 105 110

In this face rim there are openings at *f*, *f*, and similar openings on the opposite side of the wheel, each having a cutting edge projecting out along one of its sides, to scrape, 5 or cut, the soil at the sides of the ditch, and allow it to pass into the interior of the wheel, where the receivers are placed.

In Fig. 3, which represents the excavating wheel with the face rim removed, *K*, *K*, 10 are the metallic plates which form its outer rim; these as it will be seen, consist of curved segments, which in Fig. 2, are covered by the face rim, in which figure they are represented by dotted lines; *g*, *g*, are their 15 cutting edges, and as these separate the soil, it passes into the vibrating receivers *h*, *h*, *h*; the edges of which, when they are at the lower part of the machine, rest just within the cutting edges of the wheel, and as this 20 rises, the receivers swing upon joint rods *i*, *i*, *i*, and carry the earth up until the ends *k*, *k*, of the receivers are brought into contact with stops, or pins *l*, *l*, by which they are made to discharge themselves, the earth 25 falling from them on to an inclined plane, or chute *L*, *L*, (Figs. 2, 5, and 9,) the lower edge of which plane reaches beyond the excavation, and delivers the earth where it is required to form an embankment. The upper 30 edge of the plane is extended up under the buckets, as represented in Fig. 5, and supported in this position by the uprights *L*², which rests upon the shaft, or axle *C*, of the excavator.

35 *N*² is a box placed in the uprights *L*², through which the axle passes and upon which it wears. The lower end of *L*² also rests upon a part of the frame *A*, which is here extended into the wheel to receive it.

40 *O*², is a piece that extends across the bottom of the plane, and rests upon the top end of the upright.

In Fig. 2, I have represented four cutting edges, and four receivers to the excavating 45 wheel; but this number may be varied as may be found to answer best, and it may probably be found that two will be sufficient. Instead of using a wheel with serrated edges, I intend as already stated, sometimes to employ arms projecting out from the main shaft, carrying at their outer extremities, the vibrating receivers contained within suitable cutting edges, so as to operate in all respects like the wheel described. In Figs. 50 4 and 5, *M*, *M*, may represent such arms, and *m*, *m*, the cutting edges of the excavator; the sheets of metal forming the cutters, must be attached firmly to the arms and may be connected by braces as at *n*, *n*.

55 60 Fig. 10, represents a perspective view of one of the vibrating receivers, with the lugs and the bolts for adjusting them for different widths.

As it is desirable in some soils, to give a

greater slope to the sides of the ditch, than 65 in others, I, in many cases, make the cutting sides of my excavator adjustable, by means of a rod and regulating screws, as shown at *o*, *o*, Fig. 10, and by the dotted lines *o*, *o*, Fig. 5. I sometimes also place cutting teeth 70 *j*, *j*, Fig. 6, along the lower edge, and side, of said excavator, and projecting out some three or four inches therefrom, of different forms and sizes, according to the size of the ditch to be cut, by which means it will cut 75 more readily through the matted sward, and other obstructing matter. Where the nature of the ground is such as not to afford a firm footing to the horse, I attach a circular platform, or horse walk to the machine, to slide 80 along upon the ground, as shown by the dotted lines at *P*, *P*, Fig. 1, which consequently advances with the machine. To adjust the machine to the cutting of different depths, I employ an adjusting screw, *q*, *q*, 85 Figs. 2, 7, and 8, 9, which operates upon the slide *r*, *r*, upon which the axles *z*, *z* of the wheels that supports the excavator are placed.

Having thus fully described the manner 90 in which I construct and employ my machine for ditching and embanking; I do hereby declare that I claim as my invention,

1. The vibrating receivers, constructed and operating substantially in the manner 95 described, in combination with the cutters.

2. The mode of causing the machine to advance, by coiling the rope around the drum and locking it by hand, when it is desired to lessen the motion, as the lever, or sweep 100 is turned, in combination with the excavator constructed as herein described.

3. I claim the attaching of the horse walk, or circular platform, to the machine, so as to advance with it.

4. I claim the manner of adjusting the cutting wheel, of excavator, so as to cut to different depths, by means of the arrangement herein described, that is to say, by attaching the axles of the wheels, on which 110 the machine rests, to the lower part of the slides which are regulated by screws as herein described.

5. I claim the application of teeth to the side cutters as herein described.

6. I claim the mode of supporting the inner end of the chute on the axle of the excavator as herein described.

7. I claim the mode of changing the width of the ditch and the slope of the slide by 120 setting the side cutters to different inclinations as herein described, the whole being constructed and combined as herein set forth.
